UNITED STATES PATENT OFFICE

2,476,486

POWER-OPERATED WRENCH

Duncan H. Ferguson, Broken Bow, Nebr.

Application April 3, 1945, Serial No. 586,347

4 Claims. (Cl. 121—34)

1

My invention relates to improvements in power-operated wrenches, the primary object in view being to provide a simply constructed, inexpensive hydraulically-operated wrench equipped for pre-setting to predetermine the torque to be applied and which is adapted for use in applying torque to such devices as bolts, nuts, and taps and reamers, drill bits and the like, and is easy to handle and control.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in plan of my improved wrench, in a preferred embodiment thereof,

Figure 2 is a view in side elevation, partly broken away and shown in section,

Figure 3 is a view in longitudinal section taken on the line 3—3 of Figure 1 and drawn to an enlarged scale,

Figure 4 is a similar view taken on the line 4—4 of Figure 1,

Figure 5 is a view in horizontal section taken on the line 5—5 of Figure 3,

Figure 6 is a view in transverse section taken on the line 6—6 of Figure 4,

Figure 7 is a view in longitudinal section of the direction control valve,

Figure 8 is a view in horizontal section taken on the line 8—8 of Figure 3.

Referring to the drawings by numerals, my improved wrench, as illustrated therein, comprises a handle 1 of elongated straight form provided with a generally oval hollow head 2 at the front end thereof extending lengthwise from said handle. The head 2 embodies an hydraulically-operated motor which, preferably, is of the type comprising a pair of twin gear rotors 3, 4, provided with a pair of diametrically opposite impeller blades 5 adapted to revolve in twin, interlapping, substantially circular chambers 6, 7 in the head 2 which are spaced apart lengthwise of said head and are open at the top of the wrench. Each rotor is formed with a pair of diametrically opposite clearance notches 8 for the blades 5 of the other rotor, and said rotors are provided with intermeshing teeth 9 between the blades 5 and notches 8.

A cap plate 10 suitably secured to the head 2, for instance, by screws 11, closes said chambers 6, 7. The rotor 3 revolves about a tubular axial

10 arbor 12 extending axially from the bottom of a suitable hydraulic pressure gauge 13 countersunk in the top of the cap plate 10 and suitably fixed therein with a sight glass 14, a glass-retaining ring 15 and an indicating hand 16 moving over the usual graduations 17. A tubular bushing 18 surrounds the arbor 12 and to which the rotor 3 is suitably fixed, the bushing being a wear-resisting element, as will be obvious. The other rotor 4, which is farthest from the handle 1, is suitably fixed to a driven spindle 19 having one end fitted in an axial socket 20, in said rotor, said spindle extending through a bearing unit 21 in the bottom 22 of the head 2 and out of said bottom, and being equipped at its outer end with a head 23 having a spring-pressed ball detent 24 therein and for use with the usual bolt or nut-turning socket adapted, not shown. A sealing ring 25 is provided in the bottom 22 around the spindle 19 to prevent oil from escaping from around said spindle, and is secured in place by a suitable nut 26 turned into said bottom.

20 Means are provided for introducing hydraulic pressure to the described motor comprising a pair of conduits 27, 28 extending longitudinally through the handle 1 and head 2 for connection, under control of a valve, presently described, to a pair of conduits 27', 28' in said head 2 extending to opposite sides of the head 2, said conduits 27', 28' opening into the chambers 6, 7 in a common plane intersecting the common diametrical line of the rotors 3, 4 and intermediate the axis of said rotors. A pair of nipples 29, 30 are tapped into the rear end of the handle 1 in communication with said conduits 27, 28 with a pair of hose lines 31, 32 connected thereto, as at 33, 34, to be connected to the output and return sides of a suitable oil pump, not shown. Since, as will presently more clearly appear, the conduits 27, 27' on the one hand and the conduits 28, 28' on the other hand constitute inlet and discharge conduits, respectively, in one direction of operation of the spindle 19, to wit, left hand rotation, in which bolts or nuts are unscrewed, said conduits will be hereinafter referred to accordingly.

30 A settable direction control valve 35 is provided in the bottom 22 of the head 2 for reversing the direction of operation of the described motor and spindle 19. The valve 35 is of plug type rotatably fitted in a bore 36 extending into said bottom 22 from one side thereof, said valve separating the inlet conduits 27, 27' and the discharge conduits 28, 28' and being retained in said bore by a coil spring 37 and a cap nut 38. The valve 35 is provided with a pair of end transverse ports 39,

40 which, in one setting of said valve 35 are aligned with and open said inlet conduits 27, 27' and the discharge conduits 28, 28', whereas, in another setting of 90°, said conduits are cross connected by the following means. A pair of diagonal conduits 41, 42 are provided in said valve 35 which, in said other setting, establish communication between the inlet conduit 27 and the discharge conduit 28' by way of the conduit 42, and also establish communication between the inlet conduit 27' and the discharge conduit 28 by way of the conduit 41. Thus, said other setting of the valve 35 introduces pressure to the motor from the inlet conduit 27 by way of the discharge conduit 28' and permits discharge of such pressure from said motor by way of the inlet conduit 27' and discharge conduit 28 to reverse the motor and consequently reverse the wrench. A duct 43 in the bottom 22 of the head 2 extends laterally from the inlet conduit 27 to the inner end of the arbor 12 so that the pressure in the inlet conduit 27 is always indicated by the pressure gauge 13. The valve 35 has a stem 44 extending out of one side of the head and equipped with a setting lever 45 acting as an indicator hand for registration with markings on said head indicating the different settings of the valve. As will hereinafter more clearly appear, in the first-described setting, the motor is driven in a direction to operate the spindle head 23 for left hand turning of bolts and nuts, in the second-mentioned setting, the motor and spindle are reversed for operation of the spindle in right hand turning of bolts and nuts. The valve 35 is capable of being turned to a closed, or off, setting, not shown, from which it may be turned to the two previously described settings successively and also may be turned into a trial setting position intermediate the first two described settings and in which said valve is closed without reversing the wrench and a trial reading of the gauge 13 may be had. The markings on the head 2 appropriately designate the different positions of the setting lever 45 for the various settings of said valve 35.

Adjacent the head 2, a pressure-selecting valve is provided in the handle 1 for by-passing pressure from the inlet conduit 27 back into the discharge conduit 28 in advance of the valve 35. The pressure-selecting valve comprises a stem 46 threaded through a suitable packing gland 47 threaded into the handle 1 and provided at its outer end with a hand grip head 48. The inner end of the stem 46 is provided with a flange 49 bearing against a spring 50 interposed between said flange and a valve member 51 yielding urged by said spring against a seat 52 surrounding a by-pass port 53 provided between the inlet conduit 27 and the discharge conduit 28. By setting the stem 46, the pressure exerted by the spring 50 may be varied, against the valve member 51, so as to close the valve or to vary the amount of hydraulic pressure passing to the motor in a manner which will be clear.

Adjacent the rear end of the handle 1, a manually controlled valve is provided for starting or stopping the motor. The manually controlled valve 54 comprises a stem 55 extending through a packing gland 56 turned into the handle 1, the stem 55 being slidably in said gland 56 in intersecting relation to the discharge conduit 28 and provided with a conical head 57 adapted to seat in a similarly-shaped by-pass port 58 provided in the handle 1 between the inlet and discharge conduits 27, 28. A suitably arranged coil spring 59 interposed between a flange 60 on said stem 55

and a nut 61 threaded into an opening 62 in the handle 1 normally urges the stem 55 in a direction to unseat the head 57. A suitable hand lever 63 pivoted on the handle 1, as at 64, for pressing against the stem 55 provides for operating said stem in opposition to the spring 59 to seat the valve member 57.

A socket 65 is provided in cap plate 10 in axial alignment with the spindle 19 and with a spring-pressed ball detent 66 in the socket. The socket 65 and detent 66 are for use in turning hand taps, reamers, and drill bits using the wrench in the ordinary manner.

A post 67 is slidably mounted at one end, as at 68, in a longitudinal guideway 69 in the handle 1 for adjustment along said handle to project laterally therefrom and is provided with a head 70 similar to the head 23 for use with the usual socket member, not shown, for attaching the post to a bolt head, or nut, on an engine or the like, to hold the handle 1 when the wrench is being used substantially stationary. A pilot post 71 extends from the cap plate 10 into a short bushing 72 fixed in an axial socket 73 in the rotor 4 to form a bearing for said rotor at the top of the wrench. A screw 74 is threaded through the bottom of said socket 73 into the spindle 19 to hold the same in the socket 20.

The foregoing will, it is believed, suffice to impart a clear understanding of my invention without further explanation, since the operation has been set forth in connection with the description of parts.

Manifestly, the invention, as described, is susceptible of modification without departing from the inventive concept, and right is herein reserved to such modifications as fall within the scope of the appended claims.

What I claim is:

40 1. A wrench comprising a handle, a head on one end of the handle, a reversible rotary hydraulic motor in said head, a rotary spindle extending out of the head for driving the work and to which said motor is operatively connected, means to introduce hydraulic pressure to said motor forming a fluid circuit in which the motor is interposed and in which the fluid flows in opposite directions through said handle longitudinally thereof, and means to reverse the flow of fluid through the circuit and through the motor to reverse said motor.

2. A wrench comprising a handle, a head on one end of the handle, a reversible rotary hydraulic motor in said head, a rotary spindle extending out of the head for driving the work and to which the motor is operatively connected, means to introduce hydraulic pressure to said motor forming a fluid circuit in which the motor is interposed and in which the fluid flows in opposite directions through said handle longitudinally thereof, and means in said head for reversing the flow of fluid through said circuit comprising a valve having a pair of ports therein for cross connecting opposite sides of the circuit.

65 3. A wrench comprising a handle, a head on one end of the handle, a reversible rotary hydraulic motor in said head, a rotary spindle extending out of the head for driving the work and to which the motor is operatively connected, means to introduce hydraulic pressure to said motor through said handle and head to operate said motor in opposite directions, respectively, comprising a hydraulic circuit in which the motor is interposed means to predetermine the direction 70 of operation of said motor by the hydraulic pres-

sure, and means to selectively vary the degree of hydraulic pressure introduced to said motor comprising a valve for by-passing fluid from one side of the circuit to the other.

4. A wrench comprising a handle, a head at one end of the handle, a reversible rotary hydraulic motor in said head, a rotary driving spindle extending out of the head and to which the motor is operatively connected, a pair of inlet and discharge conduits, respectively, extending into said handle, a pair of inlet and discharge conduits, respectively, in said head extending to opposite sides of said motor, a valve in said head for establishing communication between the inlet conduits of the pair and between the discharge conduits of the pair to introduce fluid under pressure to one side of the motor and discharge such fluid from the other side of the motor and thereby operate said motor in one direction, said valve being settable to cross connect one of the inlet conduits with one of the discharge conduits and the other of the discharge conduits with the other of the inlet conduits to reverse the direction of flow of the fluid to and from the sides of the motor and reverse said motor, and a valve in 25

said handle for by-passing the fluid from one conduit in the handle to the other conduit in said handle to thereby stop the motor.
